(57) **CLAIM**

We claim the ornamental design for a chemical sensor cartridge, as shown and described.

DESCRIPTION

FIG. 1 is a top, front, and left side perspective view of a chemical sensor cartridge showing our new design.

FIG. 2 is a bottom, front, and left side perspective view thereof;

FIG. 3 is a bottom, front, and left side perspective view thereof with tangent edges shown;

FIG. 4 is an enlarged detail view of the front right corner of FIG. 3;

FIG. 5 is a top view showing our design;

FIG. 6 is a bottom view thereof;

FIG. 7 is a rear view thereof;

FIG. 8 is a front view thereof;

FIG. 9 is a left side view thereof; and,

FIG. 10 is a right side view thereof.

The dash-dot-dash lines define the boundary lines of the claimed design.

All other broken lines shown in the figures are included for the purpose of illustrating environmental structure and form no part of the claimed design. The solid circle members in FIGS. 2-4 and 6, not the surfaces and the broken lines immediately surrounding them, are part of the claimed design.
